UNITED STATES PATENT OFFICE.

HENRY M. LANE, OF CINCINNATI, OHIO.

DESIGN FOR A FRAME FOR STEAM-ENGINES.

SPECIFICATION forming part of Design No. 26,180, dated October 13, 1896.

Application filed August 5, 1896. Serial No. 601,810. Term of patent 14 years.

To all whom it may concern:

Be it known that I, HENRY M. LANE, a citizen of the United States, residing at Cincinnati, in the county of Hamilton, State of Ohio, have invented and produced a new, useful, and original shape or configuration of an article of manufacture—namely, of a Steam-Engine Frame—of which the following is a specification, reference being had to the accompanying drawings, in which—

Figure 1 is a side elevation of the frame complete in the cross-plane of the shafts, showing the working cylinders and the relative arrangement of the slides and shaft-bearings; Fig. 2, a side elevation of the same in the longitudinal plane of the shafts, showing the steam-chests and valve connections; Fig. 3, a plan view of the same.

The leading feature of the design is the general configuration of the frame constituting the support for the cylinders, main shaft, and operating mechanism.

The frame embodies a base portion A, having, approximately, the form of a truncated pyramid surmounted by two approximately cylindrical columns B' B², open at the front and rear, but connected by a flat web, which is extended at either side, as at b' b², the

whole forming a support for the cylinders C' C² and the operating mechanism.

Viewed from one of its longer sides the general outline of the frame is that of a pyramid frustum, within which most of the working parts of the engine are contained, with suitable openings to permit ready access for repairs, removal, &c.; while the upper part is relieved by the columns and web, into which the sides merge. The cylinders may be cast as part of the frame or bolted on subsequently.

The design here described is equally available for engines of the compound type as for those having two high-pressure cylinders.

I claim as my invention and desire to secure by Letters Patent of the United States—

The design for the frame of a steam-engine, substantially as herein described and shown.

In testimony whereof I have hereunto set my hand in the presence of two subscribing witnesses.

HENRY M. LANE.
